UNITED STATES PATENT OFFICE.

DANA K. MARSHALL, OF MANCHESTER, NEW HAMPSHIRE, ASSIGNOR TO CHARLES F. BROWN, OF READING, MASSACHUSETTS.

AUTOMATICALLY-OPERATED STRINGED MUSICAL INSTRUMENT.

SPECIFICATION forming part of Letters Patent No. 678,319, dated July 9, 1901.

Application filed March 5, 1898. Serial No. 672,689. (No model.)

To all whom it may concern:

Be it known that I, DANA K. MARSHALL, of Manchester, in the county of Hillsboro and State of New Hampshire, have invented certain new and useful Improvements in Automatically-Operated Stringed Musical Instruments, of which the following is a specification.

This invention relates to automatically-operated stringed musical instruments in which the performance is governed by a progressively-moving actuator acting by means of pneumatic devices upon string-vibrating devices and string-shortening fingers.

The invention consists in the improvements which I shall now proceed to describe and claim.

Of the accompanying drawings, forming a part of this application, Figure 1 represents a rear view of an apparatus constructed in accordance with my invention, being a vertical section through the casing of the apparatus. Fig. 2 represents a section through the casing, taken at right angles to the section shown in Fig. 1. Fig. 3 represents a section on the line 3 3 of Fig. 2. Fig. 4 represents a detail section through a portion of the apparatus, which will be referred to hereinafter. Fig. 5 represents a section on line 5 5 of Fig. 2.

The same reference characters indicate the same parts in all the figures.

Referring to the drawings, in which I have represented my invention as applied to a violin, though it will be understood that it is applicable in its entirety to other instruments of the violin class, *a* is the casing of the apparatus, and *b* is an instrument mounted in the upper part of said casing and secured by suitable means, preferably in such manner as to be readily removed from its fixings. I provide as the string-vibrating means two bands or belts *c c'*, which may be termed "belt-bows" and which extend across the instrument at the point where the bow is usually applied to the strings. The said belt-bows are mounted upon pulleys *c' c'*, which are driven by suitable means, and devices are provided whereby the lower reach of each belt-bow may be depressed, so as to make suitable contact with the strings. The pul-

leys *c'* are mounted upon two standards *c² c²* and are arranged to be rotated through the medium of driving-belts *c³ c³*, passing around pulleys which are mounted upon a driving-shaft *c⁴*, which latter is driven through suitable intermediate devices by an electric motor *d*, arranged in the lower part of the casing.

e e e e are four arms pivoted to the standard *c²* and engaging the belt-bows at their outer ends, as shown in Fig. 3. In the arrangement which I have shown in the drawings each belt-bow controls two of the strings of the violin. When either one or the other of the two arms *e* controlling each belt-bow *c* is depressed, one or the other of said strings will be vibrated; and when both arms are depressed both of the strings will be vibrated. Springs *e' e'* are provided for raising the outer ends of the arms *e*, so as to normally maintain the belt-bows out of contact with the strings. The belt-bows being continuously driven, it will be seen that by operating the arms *e*, as described, the strings can be vibrated with substantially the same results as when a bow is used.

f f, Fig. 2, designate a series of string-shortening fingers or dampers, which may consist of small blocks or buttons of wood or other suitable material, shod with material, such as felt or leather. The said fingers are arranged above the strings at suitable points and are adapted to be depressed thereon to produce the proper note or notes in a string or strings when the same is vibrated by one of the belt-bows *c*, thus performing the same function as would be performed by the tips of the fingers of a performer. Each finger or damper is attached to the end of a finger-rod *f'*, and the several finger-rods are attached to a series of small individual bellows *g g*, which I will hereinafter term "pneumatics." Springs *f² f²* act to normally keep the fingers *f* out of contact with the strings. The pneumatics *g* in the arrangement shown are adapted to be operated by suction, and when the sides of any one of them are drawn together the corresponding finger is operated, so as to press a string against the finger-board of the violin. The fingers, as here shown, are thirty-two in number, this being sufficient to cover the range of ordinary musical compositions; but

the number of fingers may of course be increased or diminished, if desired.

Four individual pneumatics or bellows g' , similar in action to the pneumatics g , are provided for operating the arms e of the belt-bows, being connected to said arms by means of rods h h .

All of the pneumatics g and g' are operated by a set of three suction-bellows i , mounted in the lower part of the casing a and continuously driven by the motor d . It is obvious, however, that with slight alterations in the construction of the pneumatics blower-bellows could be used instead of suction-bellows.

Suitable main wind-pipes i' lead from the bellows i to a wind-chest j . (Shown in transverse section in Fig. 4.) The lower part of this wind-chest consists of a single chamber j' , which is kept constantly exhausted by the three bellows i . The upper part of the wind-chest is divided by suitable partitions into a number of individual chambers or sections j^2 j^3 , corresponding to the several pneumatics g and g' and communicating with said pneumatics by means of tubes j^2 j^3 , these tubes being shown broken off at the left of Fig. 1. From each of the chambers j^2 two wind passages or ports j^4 and j^5 lead to the chamber j' and the outside air, respectively. The several ports j^4 are controlled by flap-valves k k , normally held closed by springs k' k' , and the several ports j^5 are controlled by flap-valves m m . The valves k and m are connected in pairs by means of rods k^2 k^2 , the arrangement being such that when the port j^4 is open the port j^5 is closed, and vice versa. It will be seen that when a downward movement is given to the valve k the port covered by said valve will be opened and the corresponding port j^5 , leading to the outside air, closed, so that a free passage is established between the particular pneumatic g or g' corresponding to these valves and the chamber j' . This action by reason of the exhaustion of the chamber j' causes a suction to be exerted upon said pneumatic g or g' and causes the finger f or arm e to which it is connected to be depressed.

The several valves k are connected by rods k^3 to the rear ends of a series of pivoted levers n , whose front ends are arranged to contact with a suitable actuator. This actuator, as here shown, consists of a barrel o , continuously driven by the motor d and having teeth, pins, or projections o' o' on its surface, these teeth being adapted to engage projections n' upon the ends of the levers n and to cause said ends of the levers to be raised and depressed, thereby opening and closing the valves in the wind-chest.

The teeth o' on the cylinder are arranged in accordance with a predetermined program, corresponding to the notes of a tune, this tune being produced on the strings of the violin by the operation of the fingers f and belt-bows c through the medium of the intermediate mechanism described above.

I do not confine myself to the details of construction above described, as the same may be variously modified without departing from the spirit of my invention; nor do I confine myself to the use of the wind-chest j or its equivalent and the connected parts in connection with a violin or instrument of the violin class, as the same may readily be applied by a skilled mechanic to other automatically-operated wind instruments.

It is obvious that a perforated sheet or strip or other suitable form of actuator differing from that shown could be employed to actuate the pneumatics or bellows which operate the belt-bows and string-shortening fingers.

I claim—

1. An apparatus of the character specified, comprising strings, a belt-bow extending across and adjacent to a plurality of strings, means for driving the same, and automatically-operated pneumatic devices for varying the inclination of the path of travel of the bow to apply it to and remove it from one or more of the strings.

2. An apparatus of the character specified, comprising strings, a belt-bow extending across and adjacent to a plurality of strings, means for driving the same, automatic means for varying the inclination of the path of travel of the bow to apply it to and remove it from one or more of the strings, a series of string-shortening fingers, and automatically-operated pneumatic devices for actuating said fingers.

3. An apparatus of the character specified, comprising two oppositely-inclined belt-bows crossing each other, means for driving said bows, and pneumatic devices for varying the position and angle of said bows.

4. An apparatus of the character specified, comprising a lever, a progressively-moving actuator mechanically controlling said lever, a wind-chest having two compartments, a valve controlling a passage between said compartments, a second valve controlling an outlet from one of said compartments, the said valves being positively connected together and operated by the lever in such manner as to close one while opening the other, a string-operating device a bellows for controlling the same, connected with the compartment having the outlet, and wind-producing means connected with the other compartment.

5. An apparatus of the character specified, comprising a belt-bow, means for driving it, and automatic means for varying the angular position or plane of movement of the bow to apply it to and remove it from a string or strings of a musical instrument.

6. An apparatus of the character specified, comprising two oppositely-inclined belt-bows crossing each other, means for driving said bows, and means for varying the position and angle of said bows.

7. An apparatus of the character specified comprising an inclined belt-bow, movable in a plane across a plurality of strings, means

for driving it, and means for varying the inclination of the bow to adapt it to a string or to a plurality of strings.

8. An apparatus of the character specified comprising two supporting-standards, pulleys mounted thereon, a belt-bow extending across the strings of a musical instrument and supported by said pulleys, oscillatory arms engaged with parts of said bows for deflecting said parts, and means for moving said arms to vary the position of the belts.

9. An apparatus of the character specified comprising two supporting-standards, pulleys mounted thereon, a belt-bow supported by said pulleys, oscillatory arms each having two pulleys arranged at opposite sides of one of the stretches of the bow, and means for

moving said arms to vary the position of the portion of the belt with which they are engaged.

20

10. An apparatus of the character specified, comprising a base or support having means for securing a stringed instrument, standards at opposite sides of the instrument, belt-bows supported by said standards and extending across the strings of the instrument, and means for adjusting the angle and position of said bows.

In testimony whereof I have affixed my signature in presence of two witnesses.

DANA K. MARSHALL.
